TOOTHBRUSH

David Aiken, Winnsboro, S. C., assignor of one-third to J. W. Douglass, Jr., Greenville, S. C.

Application September 23, 1939, Serial No. 296,205

1 Claim. (Cl. 15—138)

This invention relates to tooth brushes with hollow handle for containing a quantity of liquid dentifrice, including means for feeding the dentifrice out onto the brush as required.

The principal object of the invention is to provide in combination a brush head having a shank, the latter having a bore extended longitudinally therewith into a delivery port opening out laterally immediately back of the brush head, a tubular handle open at one end and equipped therewith a removable plug or stopper pierced eccentrically by a small air inlet port and having a centrally extended feed tube dimensioned to pass into the bore of the shank, whereby with the handle filled with a liquid dentifrice and held elevated relative to the brush head, the natural siphonic action of the assembly will be to feed the dentifrice down through the central feed tube out onto the brush head, air meanwhile flowing into the handle through the air inlet port to replace the discharged liquid.

Another object of the invention is to provide a self feeding tooth brush assembly for a liquid dentifrice, the same including a tubular handle open at one end, a removable plug or stopper for the open end of the tubular handle, the same having an air duct therein, a feed tube projected centrally through the stopper and extended outwardly, and a brush head mounted on the extended end of the feed tube of the stopper, the brush head having a shank with a bore or feed duct extended longitudinally therewith, with a delivery or discharge port opening out laterally back of the brush head, the said bore or feed duct being dimensioned to nicely and snugly yet rotatably receive the feed tube of the stopper, the joint between the stopper and the brush head shank being closely fitted so as to seal the air duct of the stopper when the stopper and shank are drawn together, or to admit air through the air duct into the handle, when the stopper and shank are slightly separated.

With the foregoing objects and advantages in view, with such other advantages as may appear from the specification, attention is directed to the accompanying drawing as illustrating a preferred embodiment of the invention and wherein:

Figure 1 is a frontal elevation of the brush assembly, showing tubular handle screwed down closely upon the shank of the brush head.

Figure 2 is a similar view showing the tubular handle slightly unturned from the shank for admitting air through the air duct of the stopper, 55

as in the process of feeding liquid dentifrice from the handle down into the brush head.

Figure 3 is a longitudinal section.

Figure 4 is an enlarged detail of the brush shank and connected stopper or plug for the tubular handle.

Figure 5 is an end view of the brush shank.

Figure 6 is an end view of the handle with stopper mounted therein.

10 In practicing this invention I provide an elongated hollow or tubular handle 5, closed at one end 6 and open at the opposite end 7. This handle may be of any desired material, stiff and rigid, resilient or flexible, opaque or transparent.

15 A plug or stopper 8 is provided for the open end of the tubular handle and this stopper has a short feed tube or stem 9 pierced centrally therethrough and extended outwardly. The base of this tube 9 at its juncture with the stopper is threaded as shown at 10. A small air inlet duct 11 is pierced eccentrically through the stopper 8 at one side of the feed tube 9.

20 A brush head 12 is provided, the shank 13 thereof being flared outwardly to register with the diameter of the stopper 8, and being pierced by a longitudinally extended bore 14 having a lateral opening or discharge port 15 leading from its inner end outwardly through the shank to a point immediately adjacent the bristles of the brush head. The bore 14 is dimensioned to nicely, snugly and rotatably receive and engage the feed tube or stem 9, the mouth of this bore being threaded interiorly to engage the threaded portion 10 of the tube 9, whereby the stopper 8 and shank 13 may be closely yet detachably joined.

25 The contacting faces of shank and stopper are nicely turned and smoothly fitted to form a closed joint when the elements are turned together, so that if desired air may be excluded from entering the tubular handle through the air duct 11 by the simple expedient of turning the parts closely together, or air may be admitted into the handle by merely unturning or loosening these parts slightly. The purpose of this arrangement will be later explained.

30 The feed tube 9 is preferably of such length that when the parts are turned closely together, the end of the tube 9 within the bore 14 will cover the lateral discharge port 15, though this provision is not essential to the use and operation of the device.

35 In use, the tubular handle 5 is filled with the desired liquid dentifrice, that is to say a dentifrice as fluent or almost as fluent as water, the

stopper 8 is fitted in the open end of the handle, and the brush head 12 is screwed upon the tube 9 in manner already referred to.

It being desired to eject a quantity of the dentifrice onto the brush head, the handle is slightly unturned or loosened from the shank (which action withdraws the end of the tube 9 from the discharge port 15), and the handle is held vertically up above the brush head. The liquid then flows by siphonic action from the handle down through the feed tube 9, discharge port 15, and out onto the brush head 12, air simultaneously entering the hollow handle through its loosened joint with the shank and through the air duct 11. This action and direction of flow is caused by the well known principle of the siphon as practised in the assembly here provided, due to the greater weight of the longer column of liquid in the tube 8.

After the desired quantity of dentifrice is fed out onto the brush head, the handle 5 is screwed down closely onto the end of the shank 13, thus sealing the air duct 11, and stopping further flow of the dentifrice.

As a modification, the tube 9 may be shortened so as to leave the port 15 open at all times. Then the dentifrice could be emitted onto the brush head through the tube 9 in manner already described, or by leaving handle and shank screwed closely together and jerking the handle sharply upward.

It is thought the construction, use and operation of the device will be fully understood from the foregoing description, and while I have here shown and described certain preferred features of the invention, the same may be changed or modified within the scope of the claim.

I claim:

In a device of the kind described embodying a brush head having a shank bored out axially through the rear end and internally threaded and embodying a hollow handle open at one end, a stopper for the handle opening, a feed tube seated axially through the stopper the outer end thereof being extended and threaded to threadedly seat and rotate within the complementally threaded bore of the shank, the stopper having an air duct extending endwise therethrough, laterally of the feed tube for leading air directly and continuously into the handle, the opposed faces of stopper and shank-end being formed to meet squarely for closing the air duct, as the parts are screwed together, whereby with the parts retracted for opening the air duct and the handle being turned upward, a liquid in the handle will feed by gravity down and out through the feed tube as air enters directly and continuously into the handle through the air duct.

DAVID AIKEN.
